(57) **CLAIM**

The ornamental design for a menstrual cup, as shown and described.

DESCRIPTION

FIG. 1 is a top, front, right perspective view of a menstrual cup, according to the design.

FIG. 2 is a front view of the menstrual cup, according to the design.

FIG. 3 is a rear view of the menstrual cup, according to the design.

FIG. 4 is a left side view of the menstrual cup, according to the design.

FIG. 5 is a right side view of the menstrual cup, according to the design.

FIG. 6 is a top view of the menstrual cup, according to the design; and,

FIG. 7 is a bottom view of the menstrual cup, according to the design.

The broken line shown in the drawings is included for the purpose of illustrating portions of the menstrual cup and forms no part of the claimed design.
